Hicks.

UNITED STATES PATENT OFFICE

CHARLES A. MAYER, OF BOSTON, MASSACHUSETTS

ENVELOPE OPENER

Application filed June 8, 1928, Serial No. 283,893.

This invention relates to devices for opening envelopes and the like and its object is to provide such a device having, among others, the novel features hereinafter illustrated and described.

In the drawings of one embodiment of my invention selected for illustration and description,

Fig. 1 is a front elevation;

Fig. 2, a side elevation;

Fig. 3, a horizontal section on the line 3—3, Fig. 1, looking down;

Fig. 4, a similar figure illustrating the method of using the opener; and

Fig. 5, a cross-section on the line 5—5, Fig. 1.

Referring first to Figs. 1, 2, my novel envelope opener comprises a body 1, with a lower jaw 2 to engage the lower edge of a desk or table 3, and an upwardly extended neck 4 with a threaded end 5 to receive a suitable element as a winged screw 6 with a head 7 which constitutes an upper jaw, to engage the upper face of the desk or table 3.

The body 1 has a long narrow envelope receiving mouth 8 milled or cast therein with narrow slots 9 leading rearwardly from the lips in which to seat the spring 10 and knife 11 which are locked in position as by screws 12, 13, from above.

The jaws 14, 15, formed by the mouth 8 are rounded at the (Fig. 1) left hand end or entrance to the mouth, forming a tapering opening. The lower face of the jaw 14 (Fig. 3) is slotted, as stated, to receive the rear end of spring 10 and as shown in Fig. 4, the spring is fashioned and positioned to depress, by its outer and free end, the leading end of the envelope beyond the flap edge, without depressing the flap. That results in leaving an opening beneath the flap near its upper and (Fig. 4) leading end for the entrance of the knife 11.

The knife edge is inclined longitudinally relative to the rear of the mouth, and its point is set back in the mouth 8 farther than the end of the spring 10 to avoid the envelope flap, and there is preferably a very short space between the adjacent ends of these elements longitudinally of the mouth so that the

opening beneath the flap for the knife point will be made before the knife point is reached by the envelope flap as it travels through the mouth from left to right. Great difficulty has been experienced heretofore in constructing these devices to so design one that the knife point would with certainty find the opening between the envelope back and the flap.

If the envelope as well as its flap is pressed up or down together, the knife opening beneath the flap is not created. The envelope and flap should be separated at least to the extent that they will normally separate when one is under pressure while the other is not, to create the opening, and I secure this condition by depressing the envelope only by the spring just as the envelope flap approaches the knife point.

Furthermore, if the mouth had a straight rear wall connecting the two jaws 14, 15, the envelope edge would have a chance to play and to work either up or down relative to the knife and thus cause the knife to cut in other than a straight line. I have discovered by extensive experimenting that this trouble may be avoided by providing a more or less V-shaped wall 16 at the back of the mouth 8 so that as the envelope is pressed forward or to the right, Fig. 4, and naturally inwardly, it will contact with the V-shaped wall 16 which, whether the envelope is inclined to travel up or down, will tend to center it with the knife and cause the knife blade to cut straight along the folded top edge.

To care for any ragged portion, or small detached pieces, of the envelope edge, which sometimes is created by the cutting portion in the case of inexpensive envelopes, I provide the rear wall 16 at its meeting point with the knife edge with a recess 17 which receives any such ragged or detached portions and thereby removes them from the knife edge and prevents such portion or portions from interfering with the further cutting action of the knife.

In use, Fig. 4, the envelope 18 is turned upside down, and its right hand upper corner is placed between the jaws 14, 15, with its edge against the wall 16. The envelope is then slid

toward the right, Fig. 4, and when the leading edge reaches the spring end 10 which bears upon the envelope, but not upon the flap, the envelope is pressed down upon the lower jaw 15, permitting the flap edge 19 to remain free and, from its natural tendency to spring away from the envelope, it being also unsecured by adhesive at that point, and as the envelope is slid farther to the right, the knife 11 enters beneath the flap.

Further travel of the envelope will, of course, cause the knife to sever the flap from the envelope at its top edge.

My novel construction is simple in form, inexpensive to manufacture, and more sure and efficient in action than any other that I know of.

My invention is not restricted to the precise embodiment thereof described and illustrated.

Claims:

1. An envelope opener comprising a body, knife carrying jaws on one face thereof having an envelope end depressing spring and a knife above the level of the spring end, the latter terminating in advance of the former with relation to the direction of travel of the envelope.
2. An envelope opener comprising a body, knife carrying jaws on one face thereof having a knife therein, and a downwardly extended spring positioned in the mouth and acting to bend the approaching envelope body away from and below the knife before the envelope flap meets the knife.
3. An envelope opener comprising a body, knife carrying jaws on one face thereof having a knife therein, and a spring positioned in the mouth acting to space the envelope body from its flap.
4. An envelope opener comprising a body, knife carrying jaws on one face thereof having a knife, having also a spring therein fashioned and positioned to bend the envelope body only below the knife before the former meets the knife, and a curved wall between the jaws to center the envelope relatively to the knife.
5. In an envelope opening device, a body, jaws on one face thereof, a knife between the jaws and an envelope flexing member in tandem relation to the knife also therein positioned to be effective only upon the envelope before it meets the knife, and upon the flap after it meets the knife.
6. An envelope opener comprising a pair of jaws with a knife therebetween, and an envelope end depressing member also between the jaws terminating in advance of the knife and acting on the envelope when introduced between the jaws to depress it before it reaches the knife.

In testimony whereof, I have signed my name to this specification.

CHARLES A. MAYER.
